UNITED STATES PATENT OFFICE.

ARTHUR HENRY GLEDHILL, OF HALIFAX, ENGLAND.

LEVER-CONTROL MECHANISM.

1,391,948.

Specification of Letters Patent. Patented Sept. 27, 1921.

Application filed December 13, 1918. Serial No. 266,601.

To all whom it may concern:

Be it known that I, ARTHUR HENRY GLEDHILL, a subject of the King of Great Britain, residing at Trinity Works, Halifax, in the 5 county of York, England, have invented certain new and useful Improvements in Lever Control Mechanism, of which the following is a specification.

This invention relates to control mechanism of the kind in which the position of a lever is controlled by means of a slotted gate plate, the chief object of the present invention being to provide a form of apparatus of this class which will automatically cause the 10 lever when pulled to stop in successive positions and so relieve the operator from all responsibility in guiding the lever into a holding notch or recess for effecting such purpose, the arrangement being such that the 15 lever can also be moved completely through the gate in either direction without stopping at an intermediate position when required.

According to this invention a lever or sliding member passes through a zigzag or serrated slot and is normally actuated in a lateral direction in relation to such slot by a spring or weight, the arrangement being such that when the lever is moved through 20 the length of the first oblique or slanting portion of the slot it comes to rest against the transverse portion of the next serration and on being released the spring or weight moves it in a lateral direction 25 through a transverse slot into line with the next oblique or slanting slot, in which position it can be moved to its second position, that is to say until it contacts with the transverse portion of the second serration, the 30 lever or member when released returning into line with the third oblique or slanting slot and so on throughout the number of serrations in the plate. To move the lever from one end to the other of the gate 35 without stopping it at any intermediate portion, a lateral pressure is exerted upon it by the operator during its traversing movement. The transverse portions of the serrations at opposite sides of the slot advantageously overlap one another to prevent the 40 lever or member being accidentally moved through more than one step at a time.

In the accompanying drawings:—

Figure 1 is a side elevation and Fig. 2 an 45 end elevation of a form of control mecha-

nism constructed in accordance with this invention.

Figs. 3 and 4 are similar views showing the control lever in different positions, and Fig. 5 is a plan of the slotted plate before 60 the same is bent.

A indicates the lever and B the slotted gate plate.

In the example shown the lever A is pivoted in a slot a in a quadrant a^1 which may 65 be connected with the apparatus to be controlled by a Bowden wire or other suitable connection. The free end of the lever passes through the zigzag or serrated slot b in the gate plate B and a spring a^2 or a 70 weight normally exerts a lateral pressure on the lever A and causes it to bear against one edge of the slot. One end of the spring a^2 is connected with the lever A, the other end being suitably anchored to the quadrant 75 whereby said spring normally exerts a yieldable lateral pull upon said lever. Presuming the lever to be at the initial end of the slot as shown in Figs. 1 and 2, as soon as it is pulled it turns the quadrant a^1 and moves 80 through the first slot b^1 (Fig. 5) until it comes to rest against the transverse portion b^2 and occupies the position shown in Fig. 4. The lever is now released and the spring a^2 moves it through the transverse slot b^3 85 into line with the second oblique or slanting slot b^4 and so on throughout the whole number of serrations as has already been described. Each transverse portion such as b^2 is advantageously formed with a slight 90 amount of rake to prevent the lever accidentally slipping off such portion when receiving its step by step movement.

By the invention described it is only necessary for the operator to impart a succession of straight pulls to the lever to insure its receiving the desired step by step movement. After each movement it automatically frees itself from its locked position and becomes ready for its next movement 95 and no thought is required by the operator to determine to which side of the slot the lever has to be moved to free it for its next movement as in the ordinary slotted gate type of control.

To move the lever completely through the gate at one operation in the direction of the arrow C (Fig. 5) lateral pressure is exerted by the operator upon the lever during its traversing movement in the direction of the 100 105 110

arrow C¹ and to move the lever completely through the gate in the opposite direction lateral pressure is exerted by the operator upon the lever in the direction of the 5 arrow D.

What I claim as my invention and desire to secure by Letters Patent of the United States is;—

In lever control mechanism, the combination of a plate having a slot formed with 10 ratchet teeth at each side, staggered in relation to one another, to form a continuity of inclined and transverse passages, a quadrant

pivoted to move in a longitudinal direction in relation to such slot, a lever pivoted to 15 the quadrant in such manner as to be capable of moving at right angles to the movement of the quadrant, and a spring connected at one end to the lever, and at the other end to the quadrant.

In testimony whereof I affix my signature in presence of two witnesses.

ARTHUR HENRY GLEDHILL.
